UNITED STATES PATENT OFFICE

2,443,355

PIPE CLEANER

James A. Manning, Lawrence, Mass.

Application December 14, 1944, Serial No. 568,165

3 Claims. (Cl. 131—244)

1

This invention relates to a smoker's appliance, and more particularly to a device for cleaning and sterilizing cigarette holders, cigar holders and pipes.

An object of the invention is to construct a simple device to be held in one hand whereby a pipe or the like may be flushed to remove the saliva and tarry residues which condense from the combustion of the tobacco and collect in the bottom of the bowl and pipe stem. This objectionable and smelly residue also forms in cigar and cigarette holders. Most smokers clean their smoking appliances with conventional pipe cleaners, but such swabs do not remove the tenacious deposits, and particularly the odor from these deposits. With the present apparatus a smoker is able to properly clean and sterilize a pipe or holder in a simple manner by causing a stream of hot or cold water from a faucet to flow through the pipe or holder and thus quickly and efficiently wash out the deposits therefrom.

With the present simple and inexpensive device the smoker can connect the holder or pipe with the water supply with only one hand and maintain a water tight seal between the parts, which quickly and effectively cleans out the pipe or tube.

In the drawings:

Fig. 1 is a perspective view showing the use of the device in cleaning out a pipe bowl and stem;

Fig. 2 is a top plan view of the appliance showing the water inlet tube and faucet seal;

Fig. 3 is a front plan view, partly in cross-section, showing the manner of retaining the faucet and smoking appliance seals; and

Fig. 4 is a vertical cross-section illustrating the internal construction of the device and showing the water passages therethrough.

Specifically in the drawings, numeral 1 denotes a generally circular housing having a flared offset portion 3 with an enlarged vertical water passage 5 passing downwardly through the center of the cylindrical body 1. The body and offset flared portion 3 may be made from metal produced by die casting or molded from some suitable thermoplastic material. As shown in Fig. 4, the offset portion 3 terminates in a flared end having an undercut shoulder 7 therein for the retention of a generally dome shaped resilient plug member 9, whose lower peripheral edge 11 is retained by the undercut shoulder 7. A water inlet tube 13 is centrally located through the dome shaped resilient plug 9 and terminates in an annular flange 15, which is supported around the central water bore 5 on the flat portion of the body member and thus the tube 13 is prevented from wobbling.

2

It will be observed that when desired for replacement or to obtain access to the central passage 5 the peripheral edge 11 of sealing plug 9 may be disengaged from beneath the shoulder 7. One face of the cylindrical body member 1 is cut away in a similar manner to the top portion just described to provide the undercut shoulder 17 for the retention of a larger diameter, generally dome shaped sealing plug 19 whose lower peripheral edge 21 is retained by the undercut shoulder 17. At the lower end of the water passage 5 a bottom wall thereof is formed with an angle 22 to assist in projecting water passing through the passage at right angles thereto, through a central tube member 23. This tube member 23 passes through an opening 25 formed centrally of the dome shaped enlarged sealing plug 19, and it is preferable for the inner end of the tube 23 to be rigidly affixed through an opening 27 formed in the lower end of the wall of the water passage 5.

As illustrated in Fig. 1, the user may readily hold a pipe P over the resilient large diameter plug 19 encompassing the tube 23 and by pressing the pipe bowl thereagainst secure a tight connection. Still using only one hand, the dome shaped plug 9 may be placed over the outlet of the hot or cold water faucet F and a stream of water under pressure directed into the tube 13 from whence it passes into passage 5 and outwardly through tube 23 and thus water under pressure washes and sterilizes the pipe bowl and pipe stream so that the objectionable tarry material passes outwardly therethrough and into the wash basin. Cigar holders and cigarette holders may be washed in a similar manner with equal facility. Under substantial water pressure a considerable flow of water will pass outwardly to properly flush the appliance and the arcuate outer surfaces of the plugs 9 and 19 permit a snug and watertight seal by holding the plugs in contact with the faucet and smoking appliance. This enlarged central passage 5 is also adapted to hold small pieces of soap or other cleaning material to assist in the detergent action of the water stream and to help to sterilize the appliance being cleansed. The readily removable top plug 9 permits easy access to the central passage for this purpose.

I claim:

1. A smoker's appliance for use in washing the smoke tube of a pipe, a cigarette holder or the like, comprising a substantially cylindrical body member having flattened end faces and a peripheral offset portion, dome shaped resilient plugs detachably secured in one face of the cylindrical

body member and in the outer end of the said offset portion, centrally positioned fluid openings formed in the said resilient plugs and a fluid passage formed through said cylindrical body member and said offset portion and communicating with the said fluid openings in the said plugs.

2. A smoker's appliance adapted to temporarily join the smoke tube of a pipe or the like to a source of liquid under pressure comprising a cylindrical body member having flat surfaces at opposite ends and an undercut annular depression formed in one flat surface thereof, a resilient dome shaped plug detachably mounted in said depression, an offset radial stud formed integrally with the periphery of said flat cylindrical body member, the outer end of said stud being of greater diameter than the thickness of the flat cylindrical body member and having an undercut annular depression formed therein and a resilient dome shaped plug detachably held in said last mentioned depression, said resilient plugs, said body member and said offset stud having central bores forming a continuous liquid passage.

3. A portable smoke tube flushing device com-

prising a housing member having flat faces at opposite ends, a dome shaped resilient disc secured in one of said faces of the housing member, and an integral offset portion formed on the periphery of said housing member and having a dome shaped resilient disc secured in the outer end thereof, said resilient discs, the said housing member and said offset portion having a continuous fluid passage passing therethrough.
